DESIGN FOR A PANTY GIRDLE

Abraham N. Spanel, New York, N. Y.

Application December 28, 1940, Serial No. 97,688

Term of patent 14 years

To all whom it may concern:

Be it known that I, Abraham N. Spanel, a citizen of the United States and a resident of New York, New York, whose post-office address is 1100 Park Avenue, in the city, county, and State of New York, have invented a new, original, and ornamental Design for a Panty Girdle, of which the following is a specification, reference being had to the accompanying drawing, forming part thereof, wherein:

Fig. 2 is a rear view of a panty girdle showing my new design.

The characteristic feature of my design resides in the panty girdle disclosed having a bottom portion of the specific configuration shown.

I claim:

The ornamental design for a panty girdle, substantially as shown and described.

ABRAHAM N. SPANEL.
